Primary Examiner — Leanne Was-Englehart

Assistant Examiner — Devin Kelly

(57) **CLAIM**

The ornamental design for a conductive pin, as shown and described.

DESCRIPTION

FIG. 1 is a perspective view of a conductive pin according to a first embodiment of the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a conductive pin according to a second embodiment of the present design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines depict portions of the conductive pin that form no part of the claimed design.

1 Claim, 8 Drawing Sheets
